UNITED STATES PATENT OFFICE.

GEORGE H. BARRUS, OF BROOKLINE, MASSACHUSETTS.

HEATING SYSTEM FOR SLASHERS.

Application filed May 24, 1922. Serial No. 563,251.

To all whom it may concern:

Be it known that I, GEORGE H. BARRUS, a citizen of the United States, residing at Brookline, in the county of Norfolk, State 5 of Massachusetts, have invented certain new and useful Improvements in Heating Systems for Slasher; and I do hereby declare the following to be a full, clear, and exact description of the invention, such as will 10 enable others skilled in the art to which it appertains to make and use the same.

This invention relates to dryers of the revolving cylinder type, and has to do particularly with slashers used in textile mills 15 for applying size to the warp yarn and drying the treated yarn.

In the manufacture of textiles, yarns, and the like, it is common to apply a sizing to the material before weaving. According 20 to one method frequently employed a number of strands of yarn or thread are gathered together in a sheet, as in the warp of a fabric; and passed first through a box or vat containing the size in the form of a 25 warm liquid paste, and then immediately over steam heated revolving cylinders for the purpose of thoroughly drying the size. The steam for the drying cylinders is often obtained from the exhaust of steam engines 30 used for driving the looms and various other machinery of the mill, and is supplied directly to the drying cylinders, the condensate being usually withdrawn from each cylinder through a trap and passed into a 35 common drain pipe leading to a hot well or going to waste, as desired. Sizing material is supplied to the vat and is maintained in the form of a liquid paste by adding appropriate quantities of water or 40 admitting to the size vat a portion of the steam delivered through the steam supply line for the drying cylinders.

The heating steam admitted to the drying cylinders gradually gives up its latent 45 heat to the cylinder walls and is condensed. The condensate gathers in the bottom of the cylinders, and it is accordingly desirable that some means be provided for continuously removing this accumulated water in 50 order that the cylinders may not become filled with it. It is common to provide the inner cylindrical wall of each drying cylinder with longitudinally extending buckets for the purpose of dipping up a quantity 55 of the condensed water at every revolution of the cylinder, carrying the water thus

dipped up a part of the way around the axis of the cylinder, and discharging it at the time when the bucket approaches its uppermost position. A trough or similar member 60 is commonly provided for receiving the water emptied from the buckets and discharging it from the cylinder. It has also been proposed, particularly in systems where the drying cylinders are operated at 65 relatively high speeds, to provide a siphon entering the cylinder through a hollow trunnion and dipping into the accumulated condensate at the lower portion of the cylinder. In such a system a continuous discharge 70 of the condensate will be effected provided that a sufficient pressure difference exists between the interior of the cylinder and the container into which the condensate is discharged to maintain a flow through the 75 discharge passage.

The above drainage systems are open to the objection that, while it is possible to secure a satisfactory removal of the condensate, air and other uncondensable gases 80 are not removed and will consequently accumulate within the cylinder. The air, for instance, is of greater specific gravity than the steam which is employed as heating medium and consequently tends to gravitate 85 towards the periphery of the cylinder under the influence of rotation. This blanket of air forming adjacent the heat transferring walls of the cylinder will, to a certain extent, prevent the heating steam from coming 90 into direct contact with the heat transferring surfaces and will correspondingly lower the efficiency and capacity of the system, the extent of the unfavorable influence 95 depending on the quantity of air present in the cylinder.

It is a principal object of this invention to provide an apparatus of the above general character in which both the accumulated air and water are continuously and 100 efficiently removed from the drying cylinders.

It is a further object to provide in an apparatus of this character a supplementary system, in addition to the principal means employed for discharging the condensate, which system is designed to remove the uncondensable gases from the drying cylinder, as well as a portion of the condensate and uncondensed steam, and to convey the removed fluid into the size vat or other convenient place of disposal.

It is a still further object to provide an apparatus of this character which may be conveniently and inexpensively applied to existing systems.

I have illustrated a preferred embodiment of my invention in the accompanying drawings, in which Figure 1 is a plan view of an apparatus embodying my invention, the apparatus as shown comprising two drying cylinders; Fig. 2 is an elevational view of the apparatus shown in Fig. 1; Fig. 3 is a detail view, partially in section, showing a portion of my improved system; Fig. 4 is a rear elevational view showing another manner in which my invention may be applied to existing apparatus; and, Fig. 5 is an elevational view drawn to a reduced scale showing a modified system.

Referring to the drawings, 1 and 2 indicate the cooperating drying elements of the system, here shown as hollow metal cylinders mounted for rotation about parallel axes, and 3 indicates a size vat or box positioned adjacent the drying cylinders for containing the sizing material with which the yarn or fabric is to be treated. The material to be treated is caused to dip into the sizing material by means of suitable guides or rollers (not shown) which may be provided and is passed immediately on to the drying cylinders 1 and 2 which, when supplied with a suitable heating medium, are operated in such manner as to effect complete drying of the size during the time that the material under treatment is in contact with them.

The heating steam employed in the drying cylinders may be live steam from the boilers or, as is more likely, exhaust steam from the engines and other steam utilizing apparatus commonly found in a textile mill. The steam is supplied to the drying cylinders through a line 4 communicating with a common supply main 5 which extends along the length of the apparatus and supplies the various drying cylinders through individual branches 5^a tapped off from the main 5. In addition to the supply main 5 a branch line 6 with its control valve 6^a is commonly provided so that it is possible to admit steam directly from the main supply line 4 to the size vat 3. The drying cylinders are commonly mounted for rotation on pedestals 7 or equivalent support and are provided with hollow trunnions 8 with which the steam supply lines communicate. The cylinders here shown are provided with the bucket system of drainage, the buckets 9 emptying their contents through pipes 10 into an axially extending portion discharging through a hollow trunnion 11 provided at the end of the cylinder opposite that at which the steam is admitted. If desired, the discharge of the condensate may take place through a trap or equivalent device so that the escape of

uncondensed steam is prevented. The discharge lines from the individual cylinders may conveniently lead to a common drain line 12 and the joined discharges sent to a hot well or to waste.

In Fig. 3 I have illustrated in detail the construction which I employ at the inlet end of the drying cylinder and have also shown my improved means for removing the uncondensable gases from the cylinder. The incoming steam passes through line 5^a and enters the drying cylinder through the hollow bearing 13, where it circulates about in the space within the cylinder and serves as the heating medium therefor. The hollow bearing may be of any desired construction but as shown consists essentially of the bearing sleeve 13 rotatable with the cylinder and working in the stuffing box 14 which is fixed relative to the supporting pedestal 7. Within the horizontal arm of the inlet pipe 5^a is a metallic pipe or sleeve 16 having a threaded connection at 16^a with the inlet pipe 5^a. A second pipe 17 of outside diameter approximately equal to the inside diameter of the sleeve 16 is inserted for a considerable length within the sleeve 16 and is rotatable therein. The other end of the pipe 16 extends into the interior of the drying cylinder and is connected to another pipe or extension 18 at right angles to the pipe 17 and supported in fixed relation with the cylinder by means of, for instance, a connection with the tie bolt 19 extending between the end walls of the drying cylinder. Upon rotation of the cylinder pipes 17 and 18 will likewise be rotated, the connection between the pipe 17 and sleeve 16 permitting relative rotation of the two members and at the same time affording a fluid tight joint between them.

During the operation of the apparatus the water condensate accumulates in the bottom of the cylinder and is constantly being dipped up by the buckets 9 and discharged through the hollow trunnion 11. The accumulated air within the cylinder, however, is not removed in this manner but accumulates within the cylinder. During the rotation of the cylinder the inlet end of the pipe 18 describes a circle and will pick up water condensate, steam, or air, according to the character of the medium through which it passes. I have found that when the pipe is positioned as shown at a distance from the periphery of the cylinder equal to from about one quarter to one third of its radius that a maximum of the entrapped air is removed, it being understood that the pressure within the cylinder is invariably slightly above atmospheric so that no difficulty in maintaining a continuous outflow is encountered. At the outer end of the sleeve 16 there is connected a line 20 which may be joined to a common line 21 for receiving a similar discharge from each

of the other cylinders and leading to the size box 3, a valve controlled vent 22 being preferably provided at some point along the length of the line 21 so that the discharge 5 may be diverted from the size box in case it becomes desirable to do so. The condensation in the size box of whatever steam is carried out through the line 21 serves to produce a region of pressure sufficiently reduced to maintain a continuous flow.

In Fig. 4 I have illustrated a slightly different adaptation of my invention. In this embodiment the small pipe line 21 which serves to conduct the mixed air and water 15 discharge from the respective cylinders into the size box is supplied through individual lines 20 entering at the top of the outlet pipes or branches 12^a which communicate with the interior of the cylinder. Revolving pipes 18 are provided within the cylinder as above described in communication with the lines 20, and the discharge of the accumulated air, and the like, is accomplished in a manner similar to that already 20 described, the number of pipes 18 employed being determined as desired. This embodiment possesses the advantage that the outlet trunnion and associated parts as provided on existing apparatus need not be altered. 25 In equipping the system with my invention it is merely necessary that a hole be drilled in the top of the outlet elbow 12^a for connection with the pipe 20. Furthermore, existing apparatus is usually provided with 30 a cock for letting out the accumulated air within the cylinder at starting, this cock being commonly provided on the outlet elbow 12^a. In such instances, my invention may be supplied to an existing system without 35 altering the construction of the existing parts by merely connecting the pipe 20 to the outlet cock, whereby a passage from the cylinder into the size box is afforded for the accumulated air, and the like, within 40 the cylinder. The provision for expelling air at starting may still be retained by means of a cock 22 positioned at the upper 45 end of the branch pipe 20.

I have illustrated and described my invention as employed in conjunction with the bucket system of drainage, but it is understood that it may equally well be applied to an apparatus in which other types of drainage are employed. In some bucket systems of drainage the buckets are formed at the ends of the cylinder rather than being positioned along the cylinder wall of the roller, as here shown, and it is evident that my invention may be conveniently applied to 50 a system of this type. Furthermore, I have shown only one pipe 18 extending into the cylinder for the purpose of removing air and a portion of the heating fluid but, if desired, a greater number of such lines may 55 be provided and located at such positioned

within the drying cylinder as desired so that a greater quantity of fluid may be discharged in this manner. It is even possible to secure adequate discharge of the condensate through a number of pipes 18 so 70 that any other system of drainage may be dispensed with, although I prefer to employ my invention in conjunction with one of the common drainage systems as has been described.

It is further evident that my invention may be applied to a system which is already in use with a minimum amount of additional piping, the line 21 and the individual 75 connections between this line and the respective cylinders being substantially the only new piping required. It is, therefore, obvious that a system embodying my invention may be provided at substantially the same cost as is common with existing systems, and that my invention does not add to the complexity of the apparatus.

In attaining the object of continuously removing both the accumulated air and water from the drying cylinders, I have 80 found that the apparatus illustrated in Fig. 5 may be advantageously employed. In this modification any number of drying cylinders may be employed, but I have illustrated three such cylinders. Steam is admitted 85 through the inlet line 4 into one end of the cylinder 2^a and serves to heat the drying surfaces of the cylinder. The condensate is discharged from the opposite end of the cylinder into the common drain line 12 and a 90 trap 23 is provided for the purpose of admitting only condensate into the drain line 12, passing the uncondensed vapor on through the outlet line 24, from whence it enters the inlet end of the metal roller 2 at 95 100 105 110 115 120 125 130 135 140 145 150 155 160 165 170 175 180 185 190 I claim:

1. In an apparatus of the class described, the combination of a heating member, means for admitting steam to the member, means fixed relative to said member for discharging a portion of the steam and uncondensable gases from said member and a size vat associated with said member to receive a portion of the said discharge fluid. 70
2. In a slasher having a steam heated drying cylinder and a size vat associated therewith, means for discharging condensate from said cylinder, independent means rotatable with said cylinder for withdrawing a portion of the gaseous contents of said cylinder and connections for conducting the fluid withdrawn into said size vat. 75
3. Apparatus of the class described, comprising a movable heating element, means for supplying heating steam to said element, and means fixed relative to said element for discharging a portion of the steam from said element. 80
4. Apparatus of the class described, comprising a rotatable drying cylinder, means for supplying heating steam to said cylinder, means for discharging condensate from said cylinder, and independent means rotatable with said cylinder for withdrawing a portion of the gaseous contents of said cylinder. 85
5. Apparatus of the class described, comprising a rotatable drying cylinder, means for supplying heating steam to said cylinder, means for discharging condensate from said cylinder, and independent means rotatable with said cylinder for withdrawing a portion of the gaseous contents of said cylinder, comprising a discharge outlet within said cylinder arranged intermediate the periphery and axis of rotation of said cylinder. 90
6. Apparatus of the class described, comprising a rotatable drying cylinder, an inlet pipe for supplying heating steam to said cylinder and means for withdrawing a portion of the gaseous contents of said cylinder, comprising a member having a fluid passage within said cylinder and rotatable therewith, the inlet opening of said passage lying outside the axis of rotation of the cylinder, and connections leading from said fluid passage to the exterior of the cylinder. 100
7. Apparatus of the class described, comprising a rotatable drying cylinder, an inlet pipe for supplying heating steam to said cylinder, and means for withdrawing a portion of the gaseous contents of said cylinder comprising a member having a fluid passage within said cylinder and rotatable therewith, the inlet opening of said passage lying outside the axis of rotation of the cylinder, a size vat associated with said drying cylinder and connections leading from said fluid passage to the size vat, whereby the vapors issuing from said connections are condensed in the size vat to form a region of reduced pressure sufficient to maintain a flow through said fluid passage and associated connections. 105
8. Apparatus of the class described, comprising a rotatable drying cylinder, an inlet pipe for supplying heating steam to said cylinder, and a pipe fixed relative to said cylinder for withdrawing a portion of the gaseous heating fluid from the cylinder, said pipe having its inlet opening alternately submerged in the condensate within the cylinder and lifted above the level of the condensate. 110
9. Apparatus of the class described, comprising a rotatable drying cylinder, an inlet pipe for supplying heating steam to said cylinder and means for withdrawing a portion of the contents of said cylinder, comprising a member having a fluid passage within said cylinder and rotatable therewith, a pipe extending axially of said cylinder and communicating with said fluid passage, a sleeve surrounding said pipe to permit rotation of the pipe therein, an external fluid passage associated with said sleeve for receiving the fluid issuing from said pipe, and connections associated with said external passage for conducting away the discharged fluid. 115
10. Apparatus of the class described, comprising a plurality of rotatable drying cylinders, means for supplying heating steam to said cylinders, and means for withdrawing a portion of the contents of said cylinders, comprising members having fluid passages within said cylinders and rotatable therewith, pipes extending axially of said cylinders and communicating, respectively, with said fluid passages, sleeves surrounding the respective pipes, external fluid passages associated with said sleeves for receiving the fluid issuing from said pipes, a size vat associated with said drying cylinders and a common pipe line for receiving fluid discharged from the respective drying cylinders and conducting said fluid into the size vat. 120
11. Apparatus of the class described, comprising a rotatable drying cylinder, an inlet pipe for supplying heating steam to said cylinder and means for withdrawing a portion of the contents of said cylinder, comprising a member having a fluid passage within said cylinder and rotatable therewith, a pipe extending axially of said cylinder and communicating with said fluid passage, a sleeve surrounding said pipe to permit rotation of the pipe therein, an external fluid passage associated with said sleeve for receiving the fluid issuing from said pipe, said sleeve and pipe lying within a portion of the inlet pipe. 125
12. Apparatus of the class described, com- 130

prising a rotatable drying cylinder, an inlet pipe for supplying heating steam to said cylinder, a discharge line leading from said cylinder, means for withdrawing a portion 5 of the contents of said cylinder comprising a member having a fluid passage within said cylinder and rotatable therewith, the inlet opening of said passage lying outside the axis of rotation of the cylinder, and external connections communicating with said fluid passage, said connections comprising pipes 10 entering said respective discharge lines, and a cock associated with said external connections for permitting the passage of air upon starting of the apparatus.

13. Apparatus of the class described, comprising a rotatable drying cylinder, an inlet pipe for supplying heating steam to said

cylinder, a discharge line leading from said cylinder, means for withdrawing a portion of the contents of said cylinder comprising a member having a fluid passage within said cylinder and rotatable therewith, the inlet opening of said passage lying outside the axis of rotation of the cylinder, external connections communicating with said fluid passage, said connections comprising pipes 20 entering said respective discharge lines, and a cock associated with said external connections for permitting the passage of air upon 25 starting of the apparatus.

In testimony whereof I affix my signature.

GEORGE H. BARRUS.
